UNITED STATES PATENT OFFICE.

ERIC CARSON, OF HARLEM, ILLINOIS.

VIOLIN.

No. 819,205.

Specification of Letters Patent.

Patented May 1, 1906.

Application filed October 14, 1904. Serial No. 228,420.

To all whom it may concern:

Be it known that I, ERIC CARSON, a citizen of the United States of America, residing at Harlem, in the county of Cook and State of Illinois, have invented certain new and useful 5 Improvements in Violins, of which the following is a specification.

My invention relates to certain new and useful improvements in violins; and its object is to produce a device of this class which shall have certain advantages which will appear more fully and at large in the course of this specification.

To this end my invention consists in certain 15 novel features which are shown in the accompanying drawings as embodied in my preferred form of construction.

In the aforesaid drawings, Figure 1 is a section in the line 1.1 of Fig. 2. Fig. 2 is a longitudinal section in the line 2.2 of Fig. 1. Fig. 3 is a horizontal section in the line 3.3 of Fig. 4 looking in the direction of the arrow. Fig. 4 is a section in the line 4.4 of Fig. 3. Fig. 5 is an end view of a portion of the tuning mechanism looking in the direction of the arrow 5 in Fig. 4, a certain portion of the view being shown in vertical section taken in the line 5.5 of Fig. 4, and Fig. 6 is a fragmental rear view of the device with the rear doors removed.

Referring to the drawings, A is the neck of 30 my improved device, which is made in the form of an ordinary violin-neck.

B indicates the hollow body of the instrument, the same comprising a back B', sides 35 B'', and a top or sounding-board B''. An ordinary bridge and strings (not here shown) are provided, such as are used in an ordinary violin.

At the upper end of the body is a block C, 40 to which is secured a channel-iron D, having flanges turned toward each other, as illustrated. Within this channel-iron is a laterally-movable bar E, to which are secured a plurality of strings F, preferably twelve in 45 number. A door b is provided in the side wall of the violin-body, through which this bar can be removed to attach strings when desired.

The strings F run over two bridges f, 50 which project downwardly from the top or sounding-board of the instrument and are secured to pegs g, which project up through a plate G, mounted on blocks at the lower end of the body. Below the plate G are channel- 55 irons G' G'', staggered, as illustrated in Fig. 4. Each of the pegs g is provided at its lower

end with a gear g', lying in one of the channel-irons and in mesh with a worm g'', the ends of said worms projecting out toward the rear of the body from the channel-irons G' G'' 60 and terminating in a set of square-headed keys. The staggered arrangement herein shown, which produces two sets of keys at different heights, is used only for the sake of compactness.

Doors b'' are provided in the side walls of the violin-body at the lower end, which can be opened to give access to the keys d'' for the purpose of tuning the strings F, and all but one of the keys are thus accessible. The single key which cannot thus be reached is the center key, which is covered by a plug G''' at the lower end of the violin-body and can be reached by removing the same. This plug extends through a sleeve g'', the outer end of 75 which has a head which supports the tail-piece of the instrument.

In practice the strings F are tuned in a chromatic scale to harmonize with the regular strings of the instrument, so that whenever a note is played on the instrument one of the strings below the sounding-board will vibrate in unison with said note and greatly reinforce it. In this way the volume of tone from the instrument is very largely increased. 85

A lever H is pivoted to the bottom B' of the body. At its forward end this lever carries a damper h, of felt or other material, which will prevent the sounding of the strings F when in contact therewith. The lever is 90 operated by means of a knob h', connected with the lever H by a post h''. This knob h' is in position to be operated by the chin of the user of the instrument.

I realize that considerable variation is possible in the details of this construction without departing from the spirit of the invention, and I therefore do not intend to limit myself to the specific form herein shown and described.

I claim as new and desire to secure by Letters Patent—

1. In a device of the class described, the combination with the body and neck of a violin, of a guide at the upper end of the body, a bar transversely movable in the guide through an opening in the side wall of the body, strings secured to the bar, suitable bridges over which the strings run, and means at the lower end of the body for tuning said strings. 105

2. In a device of the class described, the combination with the body and neck of a vio-

lin, of a plurality of strings secured to the upper end of the body within the same, bridges over which the strings run, keys at the lower end of the body and doors in the side wall of the body through which the keys can be reached.

In witness whereof I have signed the above

application for Letters Patent at Chicago, in the county of Cook and State of Illinois, this 25th day of August, A. D. 1904.

ERIC CARSON.
